UNITED STATES PATENT OFFICE.

ANDREW J. VAN DOREN, OF BUNKER HILL, INDIANA.

HEATING SYSTEM.

No. 904,381.

Specification of Letters Patent.

Patented Nov. 17, 1908.

Application filed June 1, 1907. Serial No. 376,749.

To all whom it may concern:

Be it known that I, ANDREW J. VAN DOREN, a citizen of the United States, residing at Bunker Hill, in the county of 5 Miami and State of Indiana, have invented new and useful Improvements in Heating Systems, of which the following is a specification.

This invention relates to improvements in 10 hot water heating systems, particularly with reference to the construction of the furnace and with reference to the construction of the boiler, and it consists in the construction, combination, and arrangement of devices hereinafter described and claimed.

One object of my invention is to simplify the construction of the furnace.

Another object is to simplify and cheapen the construction of the boiler.

Another object is to provide an improved form of furnace and boiler, which will enable the furnace and the water tubes of the boiler to be readily cleaned in a very short time, and to adapt the furnace to burn any 25 kind of fuel.

In the drawings:—Figure 1 is a vertical sectional view of boiler and furnace for hot water heating systems embodying my invention. Fig. 2 is a vertical transverse sectional view of the same, taken on the plane indicated by the line 2—2 of Fig. 1. Fig. 3 is a rear elevation of the same. Fig. 4 is a detail perspective view of the water-back of the furnace which also forms the main 35 body of the boiler.

The side walls 1 of my improved furnace may be made of any suitable material. At a suitable distance from the upper side of the furnace, and over the portion thereof constituting the fire box 2 is a baffle 3, which is horizontally disposed, is of suitable length and has its side edges seated in grooves 4 in the inner surfaces of the side walls 1.

The front end of the furnace is formed by 45 a plate 5, which is provided near its upper end with a manhole opening 6, is provided at a point opposite the fire box with a fuel feeding opening 7 and is provided near its lower end with an ash or draft opening 8. The doors 9, 10, and 11 are provided for the 50 said openings. The rear end of the furnace is formed by a plate 12, which has an opening 13 extending in rear of the fire box and also extending above the baffle 3 into the smoke chamber 14 above the fire box. The front plate 5 and rear plate 12 are provided

on their inner sides with angle brackets or flanges 15, which support the front and rear ends of the grate 16 that divides the fire box 2 from the ash pit 17. The top 18 of the 60 furnace may be made of plate or cast metal, and the same is provided in its front end with a smoke escape opening 19 for connection with a smoke pipe 20.

The boiler comprises a box or body 21 and 65 a plurality of water tubes 22. The said box or body forms a water-back for the furnace proper, and said body is provided with a projecting surrounding flange 23 that bears against the back of the furnace and is secured thereto by bolts 24. The water tubes, which are attached to the front side of said body or water-back extend longitudinally into the furnace, some of them entering and extending longitudinally through the fire 75 box, arranged at the sides thereof and under the baffle 3, and others extending longitudinally through the smoke chamber 14, over said baffle. Any suitable number of flow pipes 25 and of return pipes 26 may be attached to the said body or water-back. The front end of each water tube is closed by a suitable screw plug 27.

It will be observed by reference to Fig. 1 that all of the water tubes may be rendered 85 distinctly visible by opening the doors in the front side of the furnace, that access may be readily attained to all the interior parts of the furnace and to all of the water tubes, and hence that the furnace may be very readily 90 cleaned of accumulations of soot, so that the furnace may, with very little trouble, be kept in perfect working condition. It will be further understood that the furnace and boiler are extremely simple in construction 95 and that the same may be readily manufactured at comparatively small cost.

Having thus described the invention what is claimed as new, is:—

The herein described furnace comprising 100 a casing having side walls, front and rear plates, and a top plate, said front and rear plates and top plate being attached to and connecting said side walls, said front plate having openings and closures therefor, said 105 top plate having a smoke escape opening and said rear plate having an opening substantially coincident with the fire box and a portion of the smoke box formed above the fire box, grate bars extending longitudinally of 110 the furnace supports for said grate bars on the inner sides of the front and rear plates, a

water-back detachably secured on the outer side of the rear plate and covering the said opening therein, said water-back having flow and return pipes and being further provided with water tubes secured to the front side thereof, extending through the opening in the rear plate and into and disposed longitudinally of the furnace, terminating short

of the front side of the furnace and having removable closures for their front ends. 10

In testimony whereof, I affix my signature in presence of two witnesses.

ANDREW J. VAN DOREN.
